[57] CLAIM

The ornamental design for a urine collector, as shown.

DESCRIPTION

FIG. 1 is a top front perspective view of a urine collector showing my new design;

FIG. 2 is a top plan view thereof;

FIG. 3 is a front elevation thereof;

FIG. 4 is a right side elevation thereof;

FIG. 5 is a rear elevation thereof;

FIG. 6 is a left side elevation thereof;

FIG. 7 is a bottom plan view thereof;

FIG. 8 is a top front perspective view of a modified embodiment of the urine collector illustrated in FIG. 1;

FIG. 9 is a top plan view thereof;

FIG. 10 is a front elevation thereof.
